GEORGE I. WRIGHT, OF FLOSSMOOR, ILLINOIS.

CROSSING-GATE CONTROL.

Application filed February 2, 1925. Serial No. 6,329.

This invention relates to systems for operating or controlling safety crossing gates such as are adapted to be used at street and railway crossings, and relates more particularly to pneumatic systems of this character. Pneumatic gates for railway crossings or the like, have heretofore been used more or less commonly, but have been operated by hand pumps, so that it would require considerable time for a gate man or tower man to operate a set of gates and he could only operate a limited number of gates and gates at a limited distance from the point of control. Furthermore, as it was necessary for him to operate the pumps, it would interfere with his observation of the traffic, and as a consequence, he could not satisfactorily operate the gates at more than one, or perhaps two crossings. Furthermore, on account of the slow operation of the gates, accidents were often apt to occur, which might have been prevented if the gates could be operated more speedily.

The present invention avoids these objectionable features and provides means whereby the gates may be rapidly operated with practically no effort on the part of the operator, and he is thereby enabled to observe the traffic more carefully and may also operate a large number of gates.

The particular objects of this invention are to provide an improved system for operating crossing gates for railway crossings or the like; to provide a power actuated pneumatic system for safety crossing gates; to provide means whereby a tower man or operator may effectively operate and control the gates at a number of crossings; to provide a simple and efficient system of the character indicated which may be readily installed and which will be durable and efficient in operation; and to provide such other advantages and improvements as will appear from the following description:

In the accompanying drawings illustrating this invention:

Figure 1 is an elevational view with parts broken away or shown diagrammatically for convenience in illustration;

Figure 2 is a plan view of the power plant and controlling apparatus;

Figures 3, 4 and 5 are details showing the positions of the valves for opening and closing the gates.

As shown in these drawings 6 represents an air compressor or blower of the positive

pressure type, which is adapted to supply air under a pressure of about eight pounds per square inch and which is driven by an electric motor 7. The blower intake 8 is preferably provided with a muffler 9 to prevent undue noise, particularly when the apparatus is located in a tower, for instance as shown at 10. The blower is also provided with a release valve 11, which is enclosed in a muffler 12 having a pipe 13 leading to the atmosphere. The blower outlet pipe 14 is connected to a header pipe 15 which is preferably made sufficiently large so that it will serve in a manner as a storage reservoir for supplying air to the gates.

As shown in Figures 1 and 2, the header is provided with a sufficient number of lead pipes and control valves to operate sixteen gates or a sufficient number for four ordinary crossings. However, as these are all substantially duplicates, it will only be necessary to describe the control for a single pair of gates. A T 16 is connected to the header 15 by a nipple 17 and is connected with a four-way valve 18 having an outlet 19 leading to the atmosphere. Another outlet 20 is connected by means of a pipe 21 to the proper side of the pneumatic devices 22 for raising the gates 23. It will be understood that these gates may be of any suitable kind in which air or fluid may be utilized for raising and lowering the same.

The opposite outlet 24 of the valve 18 is connected by a pipe 25 with the opposite or lowering sides of the pneumatic devices 22 for actuating the gates. Any suitable valve may be utilized, as for instance a conical or plug valve, as shown in Figures 3 to 5, in which the passageways are opened and closed by means of a rotatable cone or valve member 26, which is actuated by a valve handle 27.

The opposite end of the T 16 is connected with a valve 28 which is the same as the valve 18 and which controls the air going to a second pair of gates, as for instance, the ones at the crossing opposite to the gates 23. It will thus be seen that the two sets of gates at a crossing are controlled by the two valves which are positioned closely together. While this is a preferred arrangement, of course the piping to the different gates may be arranged in any suitable manner to provide for different conditions.

The motor 7 is supplied with electricity from any suitable source of supply through

feed wires 29 and 30, and a switch 31 is arranged adjacent to the valves so that the operator may readily start or stop the motor without leaving his position. The capacity of the blower 6 is preferably such that, upon starting the same, it will at once supply sufficient air to operate the gates, the storage capacity of the header 15 being sufficient to insure a smooth or steady operation of the devices.

Assuming that the gates are in either raised or lowered position, the valve will be turned to close the inlet opening from the T, as shown in Figure 3. If the gates for instance are raised and the tower man wishes to lower them, he presses the switch 31 and starts the motor and blower. He then turns the valve to the position shown in Figure 4, which opens the passageway from the header 15 to the pipe 25, which will actuate the pneumatic devices of the gates and cause the gates to be closed. It will also be noted that when the valve is turned to this position, a passageway is opened from the pipe 21 through the valve to the atmosphere, which will relieve any back pressure on the gates and will permit the proper closing of the same. As soon as the gates are lowered the valve is again turned to its former position, as shown in Figure 3, and the motor will ordinarily be stopped.

When the gates are to be opened, the motor is again started and the valve is swung to the position shown in Figure 5, which will open a passageway from the header 15 to the pipe 21, which permits the air to pass to the proper side of the pneumatic devices for raising the gates 23. When the valve is turned in this position, the pipe 25 is also 40 bled through the valve in the atmosphere, as shown in Figure 5.

From actual installations of my improved apparatus, I have found that the gates may be more rapidly operated than with the ordinary manually operated gates and furthermore, a larger number of gates may be operated by a single tower man, thereby greatly reducing the cost of operation as well as increasing the efficiency of the gates. For instance, in one installation where there is a considerable amount of traffic, twelve posts or gates are controlled from one tower by utilizing my improved system.

It will be apparent that my improved apparatus is sufficiently flexible so that it may be easily adapted for different conditions and therefore I do not wish to be limited to the exact arrangement herein shown and described, except as specified in the following claims in which I claim:

1. An apparatus for operating a plurality of crossing gates comprising a motor, an air pressure blower driven by the motor, pneumatic operating devices for each of said

gates, pipes for conducting the air from the blower directly to the respective pneumatic operating devices and controlling valves for regulating the flow through the pipes to the respective operating devices.

2. Means for operating pneumatic crossing gates comprising a motor, an air compressor driven by the motor and adapted to directly furnish air at the proper pressure to mechanism for operating the gates, means for conducting the air from the compressor to said mechanism, and means for controlling the motor, the arrangement being such that the operator may start and stop the motor when the gates are to be controlled and the compressor will have sufficient capacity to furnish air directly at a pressure sufficient to operate the gate mechanism.

3. In a crossing gate control system, crossing gates and fluid pressure means for raising and lowering them, and a positive pressure blower for supplying fluid under pressure directly therefrom to the fluid pressure means.

4. The combination with a plurality of fluid pressure operated crossing gates, of a positive pressure blower, and means for directly connecting the blower to the gate operating means.

5. The combination with a plurality of crossing gates, of pneumatic means for raising and lowering them, a positive pressure blower and means for continuously operating it during such periods as the gates are to be actuated, and means for selectively connecting the blower with the pneumatic means to directly receive the full pressure of the blower in operating said means.

6. In an apparatus of the character set forth, the combination of a positive pressure blower, a motor for actuating the blower, means for starting and stopping the motor, a plurality of swinging crossing gates, pneumatic means for actuating each of said gates, said means being operable by the pressure furnished directly from the blower, pipes from the blower to the respective pneumatic means for controlling valves for said pipes.

7. A crossing gate control system for a plurality of the usual pivoted gates having pneumatic devices for operating the same, with a central station provided with a low pressure blower which supplies air at the pressure required for operating the gates, a motor for said blower, pipes leading from the blower to the respective pneumatic operating devices and controlling valves in said pipes.

8. The combination of a pivoted gate of the type commonly used for railway crossings with pneumatic means for operating the same, a positive pressure blower for furnishing air directly at the proper pressure for

- actuating the pneumatic means, connections between the blower and the pneumatic operating means, a motor for driving said blower, and means for controlling the motor.
5. 9. A crossing gate system comprising a central control station, a plurality of swinging crossing gates, pneumatic means for actuating each of said gates, a pressure blower adapted to directly furnish air at the proper pressure for operating said pneumatic means, connections between the blower and the pneumatic means for the respective gates,
- a motor for driving said blower and means for starting and stopping the motor.
10. In an apparatus of the character set 15 forth, the combination with crossing gates having gate operating mechanism, of a blower, means for directly supplying the air from the blower to the gate operating mechanism, and means controlling the operation 20 of the blower whereby it operates only when it is desired to move a gate.

GEORGE I. WRIGHT.
